BOX

Joseph P. Oman, St. Paul, Minn., assignor to
Northwestern Corrugated Box Company, Min-
neapolis, Minn., a corporation of Minnesota

Application August 2, 1934, Serial No. 738,075

11 Claims. (Cl. 229—52)

My invention relates to boxes and particularly to the closure construction thereof and has for an object to provide a closure embodying handles by means of which the box may be readily carried.

Another object of the invention resides in constructing the box with flanges folded over from the upper ends of two of the corresponding walls of the box to form a closure therefor and in providing handle members connected to said flanges.

A still further object of the invention resides in constructing said handle members as tabs disposed adjacent one another and provided with openings forming hand grips by means of which the box may be carried.

A feature of the invention resides in providing flaps on the upper ends of the other walls of the box adapted to engage the tabs to transmit the load of the box from the bottom through the wall structure and tabs to the handle members.

An object of the invention resides in constructing the flaps with downwardly facing shoulders and the tabs with upwardly facing shoulders adapted to cooperate with one another, said shoulders restraining upward movement of the tabs relative to the box structure.

A feature of the invention resides in forming the shoulders in said flaps by cutting vertically extending slots therein terminating medially of the upper and lower edges of said flaps.

A still further object of the invention resides in constructing the shoulders on said tabs by forming notches at the upper edges thereof positioned inwardly from the ends of said tabs.

An object of the invention resides in utilizing the slots in said flaps for the reception of the ends of the tabs and in disposing said flaps in inclined relation to bring the shoulders thereof into engagement with the shoulders on said tabs.

Other objects of the invention reside in the novel combination and arrangement of parts and in the details of construction hereinafter illustrated and/or described.

In the drawings:

Fig. 1 is a perspective view of a box in open position illustrating an embodiment of my invention.

Fig. 2 is a view similar to Fig. 1 showing the box in closed position.

Fig. 3 is a view similar to Figs. 1 and 2 showing the box in partly closed position.

Fig. 4 is a view similar to Fig. 2 showing the box closed and with the handle members in the plane of the closure of the box.

Fig. 5 is a sectional detail view taken on line 5—5 of Fig. 4 and drawn to a larger scale.

Fig. 6 is a developed view of the blank from which the box is constructed.

In the handling of various articles such as beer bottles and the like, considerable difficulty and inconvenience is encountered when the bottles are placed in bags and particularly when the bottles are wet. The present invention provides a simple and convenient box by means of which a number of bottles may be carried without danger of breakage of the package or contents and from which the bottles may be easily removed or inserted as the occasion requires.

My invention is constructed from a blank indicated in its entirety by the reference numeral 10 in Fig. 6. For this blank corrugated board or solid fibre board or any other suitable material may be employed. The blank is scored along two spaced parallel lines 11 and 12 which are disposed inwardly from the upper and lower edges 13 and 14 of the blank, and is further scored along three parallel transverse lines 15, 16 and 17 which are parallel to the transverse edges 18 and 19 of the blank. By means of the score lines the blank is formed with various portions which provide side walls 21 and 22 and end walls 23 and 24 of the box when the blank is folded and erected.

Outwardly of the two longitudinal score lines 11 and 12 the blank is sheared along lines 25 and 26 which lines lie in continuation of the score lines 15, 16 and 17. By means of this construction lower end flanges 21, 28, 29 and 31 are formed which when folded into overlying position and secured together provide a bottom for the box. The blank is further scored along longitudinally extending lines 34 and 35 disposed between the score line 11 and the upper edge 13 of the blank. By means of this construction upper flanges 32 and 33 are also provided which are of a height equal to one half the width of the box and when folded over form a closure for the box. These flanges issue from the walls 21 and 22 of the box. The score lines 34 and 35 further form tabs 36 and 37 which issue from the flanges 32 and 33. These tabs due to the height of flanges 32 and 33 are adapted to lie adjacent one another when the flanges 32 and 33 are folded into closing position. Issuing from the end walls 23 and 24 are flaps 38 and 39. These flaps are of a height greater than the tabs 36 and 37 and serve a purpose to be presently described in detail. For ornamental purposes the upper edges 30 of these tabs are curved as best shown in Fig. 6.

In the construction of the box the blank is first folded along the score lines 15 and 17 which bring the two edges 18 and 19 of the blank to-

gether. A strip of tape 41 is glued to the meeting edges of the walls 21 and 24 hingedly securing these walls together. When the box is desired for use the same is erected by applying pressure to the same at the folded corners of the box which causes the box to assume a rectangular form. The flanges 27, 28, 29 and 31 are next folded over and secured together as by gluing or otherwise. The box is then ready to receive the articles to be placed therein. Although I have shown a plain bottom for the box it can readily be understood that any type of bottom construction such as disclosed in my copending application for patent, Serial Number 738,076, filed herewith and bearing even date of execution, may be used in place of the bottom shown. In such case the box is particularly useful for holding bottles or other articles desired to be separated.

The two tabs 36 and 37 when the flanges 32 and 33 are folded into a position to provide a closure for the box lie adjacent one another and extend upwardly from the box. These tabs serve as handle members by means of which the box may be carried about. For this purpose the said tabs are provided with longitudinal registering openings 42 and 43 which form hand grips 44 and 45. By placing the hands through the openings 42 and 43 the box may be carried about through said hand grips.

To maintain the flanges 32 and 33 in closing position and to more readily transmit the weight of the box to the hand grips 44 and 45, the following construction is employed: In the two flaps 38 and 39 are formed slots 46 and 47 which are disposed medially of the lateral edges of said flaps and which commence at the score line 11 and terminate intermediate the upper and lower edges of said flaps. The upper ends of said slots form downwardly facing shoulders 48 and 49. These slots are of a width sufficient to receive the two tabs 36 and 37 when the same lie adjacent one another. In the upper edges 13 of the tabs 36 and 37 are formed notches 51, 52, 53 and 54 which provide hooks 55, 56, 57 and 58. Said latter construction also forms upwardly facing shoulders 61, 62, 63 and 64. When the end portions of the tabs 36 and 37 are inserted into the slots 46 and 47 the upper parts 65 and 66 of the flaps 38 and 39 above the shoulders 48 and 49 are received within the notches 51, 52, 53 and 54, the hooks 55, 56, 57 and 58 being hooked into the slots 46 and 47. This causes the shoulders 61 and 64 to engage the shoulder 49 and the shoulders 62 and 63 to engage the shoulder 48. By means of this construction the tabs 36 and 37 are locked with respect to the flaps 38 and 39 and the top structure held in closing position. It will also be noted that the weight of the box is transmitted to the handle members 44 and 45 through the end walls of the box and the flaps 38 and 39.

The method of using the top construction of my box is as follows: Where the bottles are inserted into the box at the brewery or bottling works the two flaps 38 and 39 are first folded over into the plane of the closure of the box. Flange 32 is next folded to overlie the two flaps 38 and 39. The total width of the flange 32 and the tab 36 is not in excess of the width of the box so that the upper edge 13 of the said tab falls within the confines of the box. Flange 33 is next folded to overlie the flange 32 and tab 36. At the same time a tongue 67 formed at the edge 13 of tab 37 by means of two vertically extending slits 68 is bent out of the plane of said tab and inserted into a transversely ex-

tending slot 69 formed on the flange 32 as shown in Fig. 4. This holds all of the parts in attached position, the box being rectangular in form with the closure members confined solely to the plane of the closure.

When the box is desired to be converted into a package for carrying, the tongue 67 is disengaged from the slot 69. This frees all of the closure members. The two flaps 38 and 39 and the flanges 32 and 33 are next folded outwardly as shown in Fig. 1. The two flanges 32 and 33 are then folded into closing position with the tabs 36 and 37 extending upwardly as shown in Fig. 3. The closure is then grasped by the said tabs and the same forced downwardly in between the bottles until the two flanges 32 and 33 take the position shown in Fig. 3. This brings the hooks 55, 56, 57 and 58 below the shoulders 48 and 49 of flaps 65 and 66 when the said flaps extend upwardly. The flaps may now be swung toward the tabs 36 and 37 and the ends of said tabs inserted into the slots 46 and 47. When the hooks are completely within said slots the handle members 44 and 45 may be raised which brings the shoulders 62 and 63 into engagement with shoulder 48 and likewise shoulders 61 and 64 into engagement with shoulder 49. The parts of the closure are now locked together and the weight in the box is transmitted through the end walls 23 and 24, flaps 38 and 39 to the handle members 44 and 45. If it becomes desirable, the bottles may be individually removed from the box and the closure structure subsequently closed as previously explained. Such operation may be repeated any number of times since the opening and closing of the box does not affect the strength or rigidity of the same nor does it weaken the parts of the box.

My invention is highly advantageous in that a simple and extremely practical box is provided by means of which bottled and other clumsy and awkward articles may be conveniently carried about. The box can be constructed at a nominal cost and by ordinary machinery such as is now well known in the art of box making. The weight of the box is transmitted through the handle members in a practical and effective manner so that undue strain upon any parts of the box is entirely eliminated. The closure for the box can be quickly opened or closed when it becomes desirable to fill or remove the contents of the box therefrom. The box can be closed in a manner to form a rectangular box without protruding parts which is particularly desirable when the filled boxes are stored in large quantities and it becomes necessary to place the boxes one upon the other.

Changes in the specific form of my invention, as herein disclosed, may be made within the scope of what is claimed without departing from the spirit of my invention.

Having described my invention, what I claim as new and desire to protect by Letters Patent is:

1. In a box having a bottom, and side walls and end walls connected thereto, flanges issuing from the upper ends of two of the corresponding walls and adapted to be bent into a position to form a closure for the box, handle members issuing upwardly from said flanges, flaps issuing upwardly from the upper ends of the other walls, and cooperating means on said flaps and handle members for holding said flanges in closing position and for transmitting the load on said bottom through said walls and flaps to the handle members.

2. In a box having a bottom and side walls and end walls connected thereto, flanges issuing from the upper ends of two of the corresponding walls and adapted to be bent into a position to form a closure for the box, handle members issuing upwardly from said flanges, flaps issuing upwardly from the upper ends of the other walls, said flaps having shoulders formed thereon, and hooks formed on said handle members for engagement with said shoulders to transmit the load on the bottom to said handle through said hooks. 5
3. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps and tabs being provided with juxtaposed parts and locking means on said juxtaposed parts for restraining upward movement of the tabs relative to the flaps. 10
- 25 4. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps having downwardly facing shoulders and said tabs having upwardly facing shoulders for cooperation with said downwardly facing shoulders, said shoulders restraining upward movement of the tabs relative to the flaps. 30
- 35 5. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps having vertically extending slots therein forming at their upper ends downwardly facing shoulders, said tabs having parts entering into said slots and being constructed with notches disposed inwardly from the lateral edges thereof, said notches forming shoulders for engagement with the shoulders on said tabs. 35
- 40 6. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps having vertically extending slots therein forming at their upper ends downwardly facing shoulders, said tabs having parts entering into said slots and engaging said shoulders for restraining upward movement 45 of the tabs relative to the flaps. 50
- 45 7. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps having vertically extending slots therein forming at their upper ends downwardly facing shoulders, the ends of said tabs being adapted to enter into said slots and being formed at their upper edges to form shoulders for engagement with the shoulders on said flaps for restraining upward movement of the tabs relative to the flaps. 55
- 50 8. In a box having a bottom and side walls and end walls connected thereto, flanges issuing from the upper ends of two of the corresponding walls and adapted to be bent into a position to form a closure for the box, tabs issuing upwardly from said flanges and lying adjacent one another, said tabs being constructed with registering openings for forming handles on said tabs, flaps issuing upwardly from the upper ends of the other walls, said flaps and tabs being provided with juxtaposed parts, and locking means on said juxtaposed parts for restraining upward movement of the tabs relative to the flaps. 60
- 55 9. In a box having a bottom and side walls and end walls connected thereto, flanges issuing from the upper ends of two of the corresponding walls and adapted to be bent into a position to form a closure for the box, tabs issuing upwardly from said flanges and being constructed to form handles, flaps issuing upwardly from the upper ends of the other walls, said flaps having vertically extending slots therein forming at their upper ends downwardly facing shoulders, said tabs having parts entering into said slots and being constructed with notches disposed inwardly from the lateral edges thereof, said notches forming shoulders for engagement with the shoulders on said tabs. 65
- 60 10. In a box having a bottom and side walls and end walls connected thereto, means forming a closure for the upper end of the box, a handle member overlying said closure, flaps issuing upwardly from the upper ends of two of the walls of the box, and cooperating means on said handle member and said flaps for transmitting the load on said bottom through said walls and flaps to the handle member. 70
- 65 11. In a box having a bottom and side walls and end walls connected thereto, means forming a closure for the upper end of the box, a handle member overlying said closure, flaps issuing upwardly from the upper ends of two opposite walls of the box, said handle member being of a length substantially equal to the dimension of the box between the walls from which said flaps issue, hooks on said handle member disposed inwardly from the ends thereof and shoulders on said flaps, said flaps being inclined inwardly toward each other to bring said shoulders into cooperation with said hooks. 75
